UNITED STATES PATENT OFFICE.

ALMERIN H. LIGHTHALL, OF NEW YORK, N. Y., ASSIGNOR TO HENRY A. MAURER, OF SAME PLACE.

DESIGN FOR A BUCKET OR VANE FOR WATER-WHEELS.

SPECIFICATION forming part of Design No. 31,192, dated July 11, 1899.

Application filed December 21, 1898. Serial No. 699,966. Term of patent 7 years.

To all whom it may concern:

Be it known that I, ALMERIN H. LIGHTHALL, a citizen of the United States, residing at New York, in the county of New York and State 5 of New York, have invented and produced a new and original Design for a Bucket or Vane for Water-Wheels; and I do declare the following to be a full, clear, and exact description of the same, reference being had to the accompanying drawings, forming a part thereof.

This invention relates to buckets or vanes for water-wheels.

The leading feature of my design is the two pairs of buckets or vanes of substantially the form shown, the different pairs being arranged with their openings in opposite directions and having the central dividing-walls and the sloping or flaring sides and the correspondingly-shaped back and front sides.

Another novel feature is the arrangement 20 of the two pairs of buckets of different size oppositely arranged and a hollow or indentation between the meeting inner edges of the buckets or cups.

The design is illustrated in the accompanying drawings, in which—

Figure 1 is a perspective view of the bucket or vane, and Fig. 2 is a section taken on the line $x-x$ of Fig. 1. Fig. 3 represents a section through one side of the bucket or vane, the section being taken at right angles to that shown in Fig. 2.

In the drawings, A A represent the members of one pair of buckets or vanes, and B B represent the members of the other pair.

As shown, the buckets or vanes A A are larger than those indicated by the letters B B, the former being approximately twice the size of the latter.

The members of one pair of buckets or vanes have their bases attached to those of the other pair, and the exterior of each bucket or vane is curved and is reduced from its outer edge to the point of juncture with a corresponding member of the opposite pair, 45 thus forming an indentation or hollow C of the form shown.

As illustrated in Fig. 2 of the drawings, the members of each pair of buckets are separated from their fellows by a wall or partition 50 D, which increases in thickness from its outer edge inward, the faces of the wall or partition being curved, as shown. Both the side and the front and back walls of the buckets or vanes are curved to correspond to the contour of the dividing-wall.

E represents a shank formed with the two pairs of buckets, and it consists of the portion F, adjacent to the buckets, and the two wings 60 G G.

Having thus described my invention, what I claim as new, and desire to secure by Letters Patent, is—

The design for a bucket or vane for water-wheels, substantially as herein shown and described.

ALMERIN H. LIGHTHALL.
